[57] CLAIM

The ornamental design for a figurine photograph holder, as shown.

DESCRIPTION

FIG. 1 is a rear elevational view of a figurine photograph holder in accordance with a first embodiment of our new design;

FIG. 2 is a front elevational view thereof;

FIG. 3 is a bottom plan view thereof;

FIG. 4 is a top plan view thereof;

FIG. 5 is a right side elevational view thereof, the left side elevational view being a mirror image of the right view shown;

FIG. 6 is a rear elevational view of a figurine photograph holder in accordance with a second embodiment of my new design;

FIG. 7 is a rear elevational view of a figurine photograph holder in accordance with a third embodiment of my new design;

FIG. 8 is a rear elevational view of a figurine photograph holder in accordance with a fourth embodiment of my new design;

FIG. 9 is a rear elevational view of a figurine photograph holder in accordance with a fifth embodiment of my new design; and,

FIG. 10 is a rear elevational view of a figurine photograph holder in accordance with a sixth embodiment of my new design.

The front of the embodiment in FIGS. 6/10 is substantially identical to that shown in FIG. 2.
